REFRIGERATED STORAGE UNIT

William A. Arzberger, North Syracuse, N.Y., assignor to Carrier Corporation, Syracuse, N.Y., a corporation of Delaware

Filed May 1, 1958, Ser. No. 732,200

1 Claim. (Cl. 62—451)

This invention relates to refrigerated enclosures. More particularly, this invention relates to refrigerated enclosures of the type suitable for storing foods or perishable items requiring refrigeration.

Enclosures of the type to which this invention pertains usually have a refrigeration system associated with a cabinet in such a manner that the inside of the cabinet may be maintained at a temperature below the freezing point of water. The refrigeration system employed is equipped with a control for the purpose of cycling the system off when the temperature in the air within the enclosure drops to a predetermined value. The control involved employs a thermostatic element which automatically cycles the refrigeration system on after the temperature of the air within the enclosure rises to a predetermined value. Thus, the temperature of the enclosure is maintained within a predetermined operating range determined by the cut-in and cut-out points of the thermostatic control.

During the period when the refrigeration system is maintained in operative, the temperature of the air within the enclosure or cabinet rises by virtue of leakage of heat into the cabinet. The pattern of air flow within the cabinet is such that the upper portion of the enclosure or cabinet is often subject to air of a higher temperature as relatively warm air collects at this point through flow of air by convection within the enclosure. If the thermostatic control which regulates operation of the refrigeration system is placed within the enclosure in such a manner that it senses this relatively warm air, frequent cycling of the refrigeration system will occur.

In order to overcome the frequent cycling, this invention contemplates assembling the accumulator, normally employed in the refrigeration system between the evaporator and the compressor, in heat transfer relation with the top wall of a liner member serving to define, in part, the enclosure. Under these circumstances, a relatively cool zone is created in the portion of the enclosure which is subject to flow of relatively warm air due to heat leakage.

This invention has for its chief object a provision of an improved refrigerated enclosure or cabinet arranged to provide a cold zone in the area subject to the collection of warm air due to heat leakage.

Another object of this invention is a provision of a method of refrigerating an enclosure which includes the step of orienting the elements of a refrigeration system so that, during shut-down periods, a supply of liquid refrigerant may be available for use in a heat transfer action to be effected in that portion of the enclosure subject to the collection of relatively warm air.

These and other objects of the invention will be apparent upon a consideration of the foregoing specifications and drawings in which;

Figure 1 is a sectional view in elevation of a refrigerated enclosure illustrating the invention; and

Figure 2 is a diagrammatic view of an element used

in the refrigerated enclosure and a portion of the refrigeration system used to cool the enclosure.

For the purpose of describing this invention and not by way of limitation, the invention will be described with reference to a refrigerated enclosure of the type known as a food freezer. These units enjoy widespread use under those circumstances where it is desired to maintain a quantity of frozen food in an atmosphere maintained considerably below the freezing point of water.

The refrigeration unit includes an outer shell member 10 and an inner shell or liner member 12 assembled within the outer shell member in the manner shown in Figure 1 with the assistance of a breaker strip 18 formed of a material having a high resistance to the transfer of heat. As will be observed in Figure 1, a space for the accommodation of insulation material is provided between the outer surface of the liner or inner shell and the inner surface of the outer shell.

The inner shell or liner member 12 comprises a top wall 13, a bottom wall 14, opposed side walls 15 and 16 and a rear wall 17 serving to define an enclosure having access through the front portion thereof. As will be observed from Figure 1, a door member 19 is mounted on the unit so as to permit or prevent access to the interior thereof. The door member is provided with a peripheral gasket 19 which engages the cabinet sealing surface of the outer shell to form a substantial air seal between the interior of the enclosure and the atmosphere.

Preferably, the structure defined includes a series of shelves not shown mounted within the enclosure and connected to the walls 15, 16 and 17. These shelves receive and support food to be maintained in a frozen condition.

The space within the inner shell is maintained at a desired temperature level by a refrigeration system of the condenser-compressor-expander type. In Figure 2, it will be noted that compressor 24, located proximate the refrigerated enclosure but thermally isolated therefrom, forwards hot gaseous refrigerant to a condenser 26 secured to the inner surface of the outer shell as indicated in Figure 1. Ambient air flowing in heat transfer relation with the back of the outer shell cools and liquefies the hot refrigerant which flows through a capillary 28 to an evaporator coil 30 assembled in heat transfer relation with the walls 13, 14, 15 and 16 of the inner shell member 12. The evaporator is so arranged that refrigerant flowing from the capillary traverses each of the walls indicated and flows into an accumulator 32 disposed in heat transfer relation with the top wall 13, of the inner shell as shown in Figure 2.

The accumulator serves to collect liquid refrigerant which has passed through the evaporator without being vaporized during transfer of heat which occurs in the evaporator. The accumulator 32 is provided with a line connecting the accumulator with the compressor 24 for the purpose of providing a path of flow for the vaporous refrigerant which cools in the accumulator.

As indicated above, the refrigeration system serving to maintain the enclosure at a predetermined temperature is equipped with means for automatically cycling the compressor on and off. As shown in Figure 2, switch 35 is connected in series with the compressor 24 and a source of electric power indicated by the lines L1 and L2. The switch 35 is operable in response to the temperature of the air within the enclosure. Bulb 36 located within the enclosure is connected to bellows 37 by capillary tube 38. The elements 36, 37 and 38 represent a closed system which contains a fill, responsive to the temperature of the air within the enclosure. When the temperature drops below a predetermined level, condensation of a portion of the fill occurs, causing the bellows 37 to contract, opening switch 35. This interrupts the circuit

through the motor driving compressor 34 to inactivate the refrigeration system.

With the invention contemplated herein, upon shutdown of the refrigeration system, the accumulator contains a body of liquid refrigerant disposed therein. Under these circumstances, when heat flows by radiation and conduction to portions of the parts of the unit which define the enclosure and raises the temperature of the air in the enclosure so that the air flow due to convection creates an accumulation of warm air in the upper part of the enclosure, a source of low temperature liquid refrigerant is available to lower the temperature of the accumulated warm air.

It will thus be seen that during shut-down periods the temperature of the air within the enclosure is maintained below the point at which it would be harmful to foods that may be stored within the enclosure. At the same time, the over-all temperature of the air within the enclosure is such that the unit will not cycle back on until such temperature is sensed by the bulb 36. It will be apparent that a considerable cost in the operation of such a food storage unit will be obtained by virtue of the use of a cabinet equipped with a refrigeration system of the type described herein.

It will thus be obvious that by securing the accumulator in the position indicated, use may be made of the liquid refrigerant available in the accumulator for cooling an area of the liner subject to an accumulation of relatively warm air. The bulb of the thermostatic control unit may be placed in a position within the enclosure where it may serve a more representative sample of the

air within the enclosure and so prevent too frequent cycling of the refrigeration system.

I claim:

5 In a refrigerated food storage unit including an outer upright shell member, an inner shell member having a configuration substantially complementary to said outer shell and including a top wall, means connecting the inner shell with the outer shell to form an insulation accommodating space between said shells, access means 10 serving as a front wall to define, with the inner surfaces of the inner shell walls an enclosure, a refrigeration system including an evaporator arranged to extract heat from the enclosure, a compressor, an accumulator interposed in the refrigeration system between the evaporator and the compressor, means for controlling operation of the refrigeration system to maintain the temperature of the air in said enclosure within a predetermined temperature range, said accumulator being disposed in heat transfer with and adjacent the forward portion of the top 15 wall of the inner shell member adjacent the upper portion of the access means so that liquid refrigerant collected in the accumulator will serve to cool the relatively warm air caused by localized heat leakage which flows by convection to the upper portion of the enclosure.
